CONCRETE BURIAL VAULT COVER

Paul A. Begun, Detroit, Mich.

Application June 4, 1959, Serial No. 56,210

Term of patent 14 years

(Cl. D19—1)

Fig. 1 is a perspective view of a concrete burial vault cover, showing my new design, and illustrating the top, one side and one end thereof, with the opposite side and the opposite end being substantially identical to the side and end, respectively, shown; and

Fig. 2 is a perspective view of the concrete burial vault cover but taken at a different angle.

I claim:

The ornamental design for a concrete burial vault cover, substantially as shown and described.
